UNITED STATES PATENT OFFICE.

LOUIS MYERS, OF DERBY, CONNECTICUT, ASSIGNOR TO THE WILLIAMS TYPEWRITER COMPANY, OF DERBY, CONNECTICUT, A CORPORATION OF IOWA.

TYPE-WRITING MACHINE.

No. 839,503.

Specification of Letters Patent.

Patented Dec. 25, 1906.

Application filed August 22, 1902. Serial No. 120,612.

To all whom it may concern:

Be it known that I, LOUIS MYERS, a citizen of the United States, residing at Derby, county of New Haven, and State of Connecticut, have invented certain new and useful Improvements in Type-Writing Machines, of which the following is a specification.

My invention relates in part to the combination of type-bars, key-levers for operating the same, and roller-bearings through the medium of which the key-levers transmit motion to the type-bars, also to the combination of key-levers capable of longitudinal sliding movement and a carriage-stop device controlled by the longitudinal movement of either of such key-levers, whereby the carriage may be stopped at different points by the movement of the respective key-levers.

In the accompanying drawings, Figure 1 is a plan view of a type-writing machine illustrating the invention. Fig. 2 is a side view of the same with some parts omitted. Fig. 3 is a vertical longitudinal section of a part of the same on a larger scale. Fig. 4 is a rear view thereof. Fig. 5 is a detail perspective view of a stepped stop.

1^a 1^b, &c., to 1^j represent the first bank of a system of letter-key levers capable of vertical vibratory movement for actuating the corresponding type-bars 26. In order to reduce friction between the finger key-levers 1 and the type-bars actuated thereby, the connection is made through a roller-bearing 2, mounted in the horizontal arm of a bell-crank lever 10, the vertical arm of which is connected by a link 3 with a crank-arm 4, projecting from the heel of the type-bar 26, which is fulcrumed at 5. The roller-bearings 2 between the several key-levers 1 and the bell-cranks 10 also permit sliding longitudinal movement of such key-levers in order that such key-levers may serve the further purpose of controlling a column-stop, as hereinafter described, for tabulating and analogous work. To this end, the longitudinal movement of either of such key-levers 1^a to 1^j is made to release the carriage from the escapement stop, and such movement of the several key-levers shifts to different extents a column-stop device whereby the carriage when so released from the escapement device will be stopped at different points, according to which key-lever is so shifted.

The key-levers 1^a, &c., are provided with upwardly-projecting rigid studs 6, adapted in the sliding movement of the respective key-levers to engage with the horizontal lower bar of a rocking frame 11, formed as shown partly in dotted lines in Fig. 4 and fulcrumed at 11^x in the fixed frame 38. The function of this rocking frame 11 is to retract the sliding clutch 43, forming part of the escapement device, whenever either of the key-levers 1^a, &c., is slid backward, so as to release the carriage and allow it to slide under the force of a suitable feed-movement spring until arrested by the column-stop. I have shown at 13^a a suitable feed-movement spring acting by torsion on a vertical shaft 13, on the upper end of which is mounted a semicircular gear 14, which imparts feed movement to the carriage 51 by gearing with the rack 52 thereon.

The respective key-levers 1^a to 1^j in their rearward horizontal sliding movement contact with projecting tappet-studs 12^a to 12^j, projecting from the bottom bar of the stop-frame 12, which is of approximately triangular form, as shown in Fig. 4, and rocks on a horizontal axis 12^x. The rocking frame 12 carries at its upper end a stepped stop 12^y of triangular shape, formed with an oblique range of steps a b c, &c., to j, as shown in Fig. 1 and in detail in Fig. 5, the construction being such that the different lengths of the tappet-studs 12^a 12^b, &c., with which the respective key-levers 1^a 1^b, &c., come in contact will rock the frame 12 to a different extent, so as to bring one or other of the steps a b c, &c., of the stop 12^y to effective position, according to which of the key-levers 1^a 1^b, &c., is slid backward.

To engage with the stepped stop 12^y—that is to say, with either of the steps thereof which is placed in the path thereof, as above described—the rocking semicircular gear 14 is provided with a range of sliding column-stops 17, which are swiveled in radial position on studs 16 through the medium of horizontal slots 17^x, Fig. 3, in the shank of said stops, permitting them to be slid forward and depressed into the position shown in dotted lines in Fig. 3, with the upwardly-inclined free end of such sliding stop 17 caught beneath the overhanging shoulder of the semicircular rocking gear. 17^y represent springs

tending to throw the sliding stop 17 up into inoperative position when slid backward, and 17^a a stop-bar which limits their upward movement.

5 Any number—eight, more or less—of the sliding column-stops 17 may be mounted in the radial position shown in Fig. 1 in the oscillating semicircular feed-gear 14 for stopping the sliding carriage at any one of as many different points in its movement.

15 represents a semicircular scale on the oscillating gear 14, corresponding with the scale on the carriage.

In operation the sliding column stop 17, which is to be brought into use, is readily depressed and slid into operative position by depressing its inclined free end by the thumb and then sliding it forward by the application of a finger to its rear end until the free end is caught beneath the overhanging shoulder of the oscillating feed-gear. To stop the carriage on a particular column indicated by any number on its scale, the proper key-lever 1^a or 1^b, &c., is slid backward, so as to throw 25 the stepped stop 12^y forward to the proper extent to present one of its steps *a* or *b*, &c., to the projecting column-stops 17, which will be arrested thereby on the release of the carriage by the contact of the stud 6 of the said 30 key-lever with the rocking release-frame 11.

Any one of the several column-stops 17 is selected and depressed to locate the column of figures in the desired position on the sheet, and the proper adjustment of the stepped 35 stop 12^y by sliding the selected key-lever 1^a, &c., determines the value of the first figure printed, to represent units, tens, hundreds, &c., and the successive figures of the whole numbers are then printed by the ordinary 40 manipulation of the printing-key.

By the use of letter-key levers for actuating the column-stop device I am enabled to tabulate by the use of the letter-keys, and thus dispense with the necessity for additional or special keys for this purpose. The 45 key-levers 1^a, &c., are made removable by forming them at their rear end with open slots 7, as indicated in dotted lines in Fig. 2, by which they slide horizontally on fulcrum- 50 rod 8.

9 represents tension-springs which may be attached at one end to the bell-crank levers 10, as shown, and at the other end adjustably in oblique notches 9^a in the key-levers, so as 55 to slide the latter forward into normal position when released from the rearward pressure applied thereto to operate the column-stop, as described. Said spring also serves to restore the type-bars 26 to normal position 60 by drawing back the vertical arms of the

bell-cranks 10 and by the same movement raise the key-levers to normal position when depressed in printing.

A lever 71, pivoted to the escapement-link 29 and fulcrumed at 72, operates the pawl 73 65 and ratchet-wheel 74 of the ribbon-shift mechanism in customary manner.

Having thus described my invention, the following is what I claim as new therein and desire to secure by Letters Patent: 70

1. In a type-writing machine, the combination of a vibrating key-lever capable of longitudinal sliding movement; a carriage-stop device operated by the longitudinal movement of said key-lever; a type-bar 75 operated by vibratory movement of the key-lever; a lever connection through which the key-lever operates the type-bar; and a roller-bearing between the said key-lever and lever connection to facilitate the longitudinal 80 movement of the key-lever, substantially as described.

2. In a type-writing machine, a key-lever 85 vibrating in a vertical plane and capable of longitudinal sliding movement; in combination with a carriage-stop device operated by the longitudinal movement of said key-lever.

3. In a tabulating device for type-writing machines, the combination of a plurality of vertically-vibrating key-levers capable of 90 longitudinal sliding movement; a carriage-stop and escapement device operated by the longitudinal movement of either of such key-levers; and tappets moved to unequal extent by the sliding movement of the several key-levers whereby the sliding movement of the carriage is arrested at different points by the 95 sliding movement of one or other of said key-levers.

4. The combination of vertically-vibrating 100 key-levers 1^a, 1^b, 1^c, capable also of longitudinal sliding movement; type-bars 26; suitable connections through the medium of which said type-bar levers are actuated by vertical movement of said key-levers; escapement-lever 11 actuated by the longitudinal movement of either of said key-levers; rocker-bar stop-lever 12, having stop-tappets 105 12^a of unequal prominence engaged by longitudinal movement of the several key-levers 110 so as to move the rocker-bar stop-lever 12 to different extent; and the stepped stop actuated by the lever 12 and the stop-dog carried by the carriage-spring gear-wheel to arrest the movement of said gear at different points 115 according to the adjustment of the lever 12.
